UNITED STATES PATENT OFFICE.

CHARLES W. GRAHAM, OF HUNTINGTON, NEW YORK, ASSIGNOR TO AMERICAN CAN COMPANY, OF NEW YORK, N. Y., A CORPORATION OF NEW JERSEY.

AUTOMATIC FEED FOR SHEET-METAL CAN-HEADS.

1,126,194.

Specification of Letters Patent.

Patented Jan. 26, 1915.

Application filed August 12, 1912. Serial No. 714,492.

To all whom it may concern:

Be it known that I, CHARLES W. GRAHAM, a citizen of the United States, residing in Huntington, in the county of Suffolk 5 and State of New York, have invented a new and useful Improvement in Automatic Feeds for Sheet-Metal Can-Heads, of which the following is a specification.

This invention relates to an automatic 10 feed device for a stack of nested sheet metal can heads and the invention consists in the novel devices and combinations of parts and devices more fully hereinafter set forth and made the subject matter of the claims.

15 In the accompanying drawing which forms a part of this specification, Figure 1 is a vertical section of my improved automatic sheet metal can end feed; Fig. 2 is a similar section showing a can end in the act 20 of being delivered from the feed; Fig. 3 is a horizontal section taken on the line 3—3 of Fig. 1; Fig. 4 is a vertical section of the feed mechanism taken at right angles to the sections indicated in Figs. 1 and 2.

25 The mechanism of the present invention is designed to handle the stack of sheet metal, nested can ends and to deliver them one at a time to the tops of cans. The mechanism comprises an open bottomed 30 stack carrier provided at two diametrically opposite sides, with a pair of rotating shafts each carrying at its lower part, a mutilated rotating disk, that acts to support the can ends in the stack to separate the lowermost 35 one from the stack and to force said lowermost one out of the device, through holding devices. The holding devices or retaining members are arranged also at opposite sides of the stack carrier and each 40 consists of a rounded projection held yieldingly in the path of the can ends below the open bottom of the carrier, and acting to retain said can ends until they are pushed down clear of the grasp. The mutilated 45 separating disks are made flat on top, to support the can ends during a part of their revolution, and each is provided with a sharp edge or point adapted to enter above the lowermost one of the can ends in the 50 stack to cause a separation of the nested ends, said disks being mutilated for a part of their circumference to permit the ends to pass by. From the sharp edges, the thickness of the disks is gradually increased, so 55 that the disks thus act to force the can ends

down past the yielding retainers and discharge them.

In the said drawing, A is the tubular stack carrier.

B, B are the vertical shafts placed at opposite sides of the stack carrier, and having each one at its lower extremity, a separating and supporting disk C, said disk being made with a sharp edge D, a thick part D¹ and a flat riding surface D². At right angles 60 to the position of the shafts B are the yielding holders E, E, having the rounded projections E¹. A yielding character is given to these holders by the springs F, F.

G, G are the sheet metal can ends, which 65 may be of the nesting variety, and are arranged in a stack within the tubular carrier.

The operation is as follows: A stack of the sheet metal can ends is placed in the tubular carrier, the lowermost can end resting upon the flat surfaces of the rotatable disks, C, C. When the machine is started and the disks C, C, are rotated by means of suitable gearing, the operation is as follows: The supporting disks revolve until 70 the mutilated parts are presented to the can ends, whereupon the stack of can ends falls down until the lowermost one encounters the retaining projections E¹, which arrest 75 farther descent of the stack. The disks continuing to revolve, the sharp edges are caused to enter above the lowermost can end of the stack and to wedge it gradually 80 downward away from the rest of the stack and against the yielding resistance of the 85 holders until it is clear of the latter and delivered to the point desired. This operation is repeated at each revolution of the feeding disks until the stack of cans is 90 completely fed. The action, it will be noted, is 95 entirely automatic, and the can ends are delivered with certainty and precision, and separated from each other by force thus preventing the ends from sticking together.

I claim:

1. In a device for feeding articles, an article holder adapted to hold articles in a nested position, rotary separating, supporting and ejecting devices located at approximately diametrically opposite points adjacent to said article holder, movable retaining devices located at approximately diametrically opposite points adjacent to said article holder, said retaining devices being positioned to allow the articles in the holder 105

to rest at a predetermined distance in advance of the supporting surface of the rotary separating devices to thus permit the separating device to enter between one or 5 more articles and eject same from said holder.

2. In a device for feeding articles, an article holder adapted to hold articles in a nested position, means for separating an 10 article from the stack of nested articles, movable retaining devices normally holding the nested articles within the article holder, said retaining devices being movable to release articles from said holder by contact of 15 an article being moved by the said separating means.

3. In a device for feeding articles, an article holder adapted to hold articles in a stack, rotary separating, supporting and 20 ejecting devices, and movable retaining devices, the ejecting devices and retaining devices being adapted to alternately support the stack of nested articles, and the ejecting devices having portions thereof arranged to 25 enter between the lowermost article of the stack and the remainder of the stack to positively separate it from the stack and force it past the retaining devices, substantially as specified.

30 4. In a device for feeding articles, a holder adapted to hold a stack of nested articles, two rotary devices positioned adjacent said holder and on opposite sides thereof having portions thereof adapted to enter the holder, said portions having plain supporting surfaces and inclined bottom surfaces, each of said devices having a pe- 35

ripheral cut-out portion adapted to permit the stack of articles to move past the same when said portions are turned upward toward each other, and retaining devices which are caused to be displaced to release an article by the action of the inclined bottom surfaces of the said rotary devices; substantially as specified. 40 45

5. In a separating and feeding device of the character described, in combination: a magazine adapted to hold a stack of articles; yielding means adapted to support a stack of articles within the magazine; and devices, 50 located above said means, having portions thereof arranged to separate the lowermost article from the rest of the stack, to positively force the separated article past said means and to temporarily support the remainder of the stack, substantially as specified. 55

6. A device of the character described including, in combination: a magazine adapted to hold a stack of articles; yieldingly held members at the bottom of said stack and normally in the path thereof and adapted to support the stack; and rotatable disks located above said members, each of said disks having a cut-out portion on its periphery and a wedge acting flange adapted to cut-out the lowermost article of the stack and force the same past said members, substantially as specified. 60 65

CHARLES W. GRAHAM.
